REFRIGERATED MEAT CHOPPER HAVING A REMOVABLE CASING SECTION

Arnold W. Lundell, Byram, Conn., assignor to Globe Slicing Machine Co., Inc., Stamford, Conn., a corporation of New York

Application October 3, 1952, Serial No. 313,009

5 Claims. (Cl. 146—182)

This invention relates to couplings for meat choppers in general and more especially to a coupling device for a refrigerated meat chopper casing associated with a refrigerating unit.

Among the objects of the present invention it is aimed to provide an improved coupling for a meat chopper having a stationary and a removable section, said sections having complementary contact faces with a projection extending from one contact face and a first recess formed in the other contact face to receive said projection, an enlargement extending from the face of said stationary contact and a second recess in the removable section to receive said enlargement, feed and return conduits extending through said stationary section and having portions protruding from the face of said stationary section, a passage or conduit formed in the wall of the removable section and having feed and return ends terminating in its face to register respectively with the protruding portions extending from the face of said stationary section, the enlargement being spaced from, and interposed between, said projection and said protruding portions, with the projection longer than said enlargement and said enlargement longer than said protruding portions whereby during assembly said projection will first be located, then said enlargement and finally said protruding portions so that said protruding portions will be protected from injurious contact with the removable section during assembly.

It is still another object of the present invention to provide an improved coupling for a two sectional meat chopper casing having a stationary section having a main plane contact face, the stationary section provided with a journal for the shaft of the advancing screw and supporting parts of the inlet and outlet conduits of the refrigerating system with the ends thereof protruding from said main plane contact face, the removable section having a second main plane contact face including the inlet funnel and the chambered cylinder for the advancing screw with a spiral passage for the refrigerant formed in the wall of the cylinder and terminating in complementary inlet and outlet openings in said second main contact face positioned to receive the protruding portions of the inlet and outlet conduits formed in said stationary section, valves for said inlet and outlet openings, and a clamping device for drawing the two main contact faces into intimate engagement with one another, thereby to seal off any leakage from the chamber for the advancing screw and effecting the actuation of the valves to seal the passage for the heat transferring medium.

These and other features, capabilities and advantages of the invention will appear from the subjoined detailed description of one specific embodiment thereof illustrated in the accompanying drawings, in which

Fig. 1 is a side elevation of the refrigerating unit motor and meat chopping unit, with the meat chopping unit in section.

Fig. 2 is an enlarged plan view of the refrigerating unit on the line 2—2 of Fig. 1.

Fig. 3 is an enlarged sectional detail of the complementary parts of the heat transferring medium where the fixed and removable sections meet.

Fig. 4 is a sectional detail exploded of the complementary parts shown in Fig. 3.

Fig. 5 is an enlarged longitudinal section of the meat chopping unit showing the two main sections separated.

Fig. 6 is an enlarged fragmental perspective showing

2

the two main sections of the meat chopping unit separated.

Fig. 7 is an enlarged transverse section of the cam device for clamping the two sections together.

5 Although refrigerating systems have heretofore been connected to meat chopping casings, these did not lend themselves for practical purposes to be connected with meat chopping machines, such as disclosed in applicant's Letters Patent No. 2,539,448, issued January 30, 1951, 10 where the casing is composed of two sections to facilitate cleaning and the like by the shopkeeper. One of the objects of the present invention, therefore, is to provide in association with a cooling system a coupling for a meat chopping machine of the type disclosed in applicant's patent aforesaid which will not only retain all 15 of the advantages of such meat chopping machines, but in addition have the advantage of cooling the same without in any way encumbering a meat chopper made according to applicant's said patent, and retain not only all 20 of the advantages of such prior meat chopping machine, but possess many additional advantages.

With applicant's invention it will be seen that the advantages, in the interest of sanitation of providing a two section meat chopping casing, including the fixed section 1 and the removable section 2, such as disclosed 25 in applicant's aforesaid patent, are retained and the meat chopper 3 may be located on the store counter or any other convenient location without regard to the location of the refrigerating system 4, the removable section 2 may be removed from the section 1 just as heretofore 30 to facilitate cleaning the chamber 5, the advancing screw 6, perforated disk 7, and rotary cutter 8, and the removable section in turn may be replaced in operative relation not only for cutting meat but also in airtight 35 relationship with the refrigerating system 4 by merely repositioning the several parts, such as the screw 6, perforated disk 7 and cutter 8, and then by means of the projection 9 fitting in the recess 10, and the cylindrical enlargement 11 fitting in the cylindrical recess 12, to 40 cooperate with one another as indices properly to position the sections 1 and 2 in a predetermined position where the tapered protruding portions 13 and 14 of the inlet and outlet conduits 15 and 16, respectively, extending from the section 1 will register with the ends 45 17 and 18 of the tube in the section 2, the plane contact faces 19 and 20 of the sections 1 and 2, respectively, will in turn cooperate with one another effectively to 50 seal the rear end of the chamber 5 formed in the casing section 2 and also to aid in sealing the connections between the protruding portions 13 and 14 of the conduits 15 and 16, respectively, extending from the section 1 and the ends 17 and 18 of the tube in the section 2 when the clamping device 21 journaled in the section 1 is turned in engagement with the projection 9.

55 The refrigerating system or unit 4 in the present instance is mounted on the platform 22 having a motor 23 at one end operatively connected to a pump mounted in the casing 24 to draw the heat transferring medium, water as an instance, through the conduit 25 and then 60 forcing it up into and through the conduit 15 to the passage 26 in the casing 2. From the passage 26, the medium is then forced down through the inlet conduit 16 into the coil portion 27 and up to the conduit 25.

65 As the heat transferring medium passes through the coil portion 27 adjacent the refrigerating coil portion 28, the heat transferring medium will be cooled. In order to replenish the heat transferring medium as an instance, if it is water a reservoir 29 may be provided 70 having an inlet 30 and a feed conduit 31 from the reservoir 29 to and in communication with the conduit 15.

The refrigerating coil portion 28 is connected by the conduit 32 to the condenser coil portion 33 and from the condenser coil portion 33 by means of the conduit 34 to the combined compressor and motor 35, and from the compressor 35 by means of the conduit 36 back to the refrigerating coil portion 28. The compressor 35 is provided with the conventional fan 37 to direct air at the condenser coil portion 33 to aid in condensing the refrigerating medium being circulated therethrough. The refrigerating medium may be any of the conventional mediums today extensively used, such for instance

as Freon. In the present instance, of course, the refrigerating medium is contained in a closed system and similarly the heat transferring medium is contained in a closed system and similarly the heat transferring medium is contained in a closed system.

The platform 22 on which the refrigerating unit 4 is mounted in the present instance is connected to the platform 38 by the rods or bars 39, 40, 41 and 42. Obviously, however, without departing from the spirit of the invention, this refrigerating unit may be located in another room as an instance, in which case the conduits 15 and 16 of course would be materially increased in length. However, since the conduit portions 15 and 16 between the refrigerating unit 4 and the casing section 1 preferably are enclosed in insulating shields 43 and 44 throughout, only parts of the shields 43 and 44 being shown adjacent the bracket 45 to which the casing section 1 is fixed, the effect on the heat transferring medium, water as an instance, will be immaterial if the lengths of the conduits 15 and 16 are increased to accommodate such remote positioning of the refrigerating unit 4 relative to the meat chopping unit 3.

Associated with the meat chopping unit 3 as disclosed in the patent aforesaid, there is provided a motor 46 mounted in the present instance on the platform 38 which is provided with a coupling 47 to receive the angular portion 48 of the shaft 49 fixed in the present instance to the advancing screw 6. The coupling 47 as shown in Figs. 1 and 5 is preferably spaced from the inner face of the bracket 45, to the outer face of which the section 1 of the casing 3 is fixed.

The section 2 preferably is provided with an upward extension 50 which is preferably chambered at 51 as shown and provided with an inner machine finished plane contact face 19 from the lower portion 53 of which there extends the cylindrical enlargement 11 provided with a central opening 54 in which the shaft 49 is journaled. The bracket 45 and section 1 below the opening 54 in the present instance is provided with aligned openings, as an instance, the openings 55 and 56 in the bracket 45 registering with the openings 57 and 58, respectively, in section 1 to receive the conduits 15 and 16 and permit the protruding portions 13 and 14 of the conduits 15 and 16, respectively, to protrude from the face 19 below the cylindrical enlargement 11. Preferably the protruding portions 13 and 14 as shown are tapered or beveled, as shown in Figs. 5 and 6.

The opening 10 in the section 1 in the present instance extends parallel with the opening 54 and openings 57 and 58 and is cylindrical in conformation. This opening 10 as shown communicates with the cylindrical opening 59 extending transverse to the direction of the opening 10 and intersecting one another approximately a 25% quadrant of the cylindrical opening 59 and in turn also approximately a 25% quadrant of the opening 10. Furthermore, the opening 59 preferably extends into the section 1 through one side of the section 1 as shown to receive the cylindrical bar 60 of the clamping device 21. The cylindrical bar 60 in the present instance is provided with an annular recess 61 to receive the set screw 62 and rotatably anchor the bar 60 in the section 1. The outer end of the bar 60 is preferably provided with a handle 63. The clamping function of the clamping device 21 is performed by the portions of the bar 60 adjacent the approximately 90° cylindrical recess 64 formed in the bar 60 at right angles to the axis thereof. The radius of the recess 64 in turn conforms to the radius of the opening 10 and the cylindrical projection 9 so that when the recess 64 registers with the opening 10 to clear the cylindrical passage through the opening 10, the projection 9 may be inserted into the same. The projection 9 in turn has a substantially 90° cylindrical recess 65 formed therein at right angles to the axis of the projection 9, the radius of which in turn conforms to the radius of the opening 59 so that when the projection 9 is positioned in the opening 10 and the bar 60 is rotated angularly, it will move the uninterrupted portion of the bar 60 into the recess 65 and draw the contact faces 19 and 20 into intimate engagement with one another. In order to effect such forced engagement, preferably the distance from the outer edge of the opening 59 to the contact face 19 will be greater than the distance between the inner edge of the recess 65 to the contact face 20.

The casing section 2 preferably as shown has the

chambered funnel extension 66 which is chambered at 52 on the outside as shown. The chamber of the funnel extension 66 communicates with the chamber 5 to enable the meat to be cut to be fed to the advancing screw

5. The advancing screw 6 in the conventional way has fixed thereto the cutter 8 anchored in rotatable engagement with the inner face of the disk 7 which is in turn locked to the outer end of the cylindrical portion 67 of the casing section 2 by the locking ring 68.

10. The wall of the cylindrical portion 67 between the funnel extension 66 and the outer end thereof, as shown, has a spiral passage 26 formed therein terminating at the face 20. Excellent results have been achieved when the spiral passage 26 is formed by placing a metal tube 69, composed as an instance of copper, nickel or the like, in the casting mold before introducing the molten mass, such as iron, aluminum, or an alloy of about 20% nickel and about 80% iron known in the trade as "Niresist." Preferably the tube 69 so placed in the mold before the molten mass is introduced terminates at the contact face 20 in the flaring ends 17 and 18 to receive the tapered protruding portions 13 and 14 when the clamping device 21 is turned to cause the contact faces 19 and 20 intimately to engage one another. As aforesaid, these contact faces 19 and 20 are accurately planed so that they will intimately engage one another throughout their surfaces when the clamping device 21 is turned to clamp them into intimate engagement with one another.

20. With the present invention, water is preferably used as the heat transferring medium so that when the casing section 2 is separated from the casing section 1, there will be no loss in the heat transferring medium, since obviously whatever water, previously retained within the system which escapes, will be resupplied from the reservoir 29.

25. One of the main features of the present invention resides in the mechanism whereby the water disposed in the tube 69 will be retained in the same and not be lost when the casing 2 is removed for the purpose of cleaning and the like, and similarly that the water in the conduits 15 and 16 will be captured and protected from evaporation or escape when the casing 2 is so removed. For this purpose, see particularly Figs. 3 and 4, two complementary valve sets are provided, one complementary set in the ends 13 and 17, and the other in the ends 14 and 18.

30. In the first place as aforesaid, the outer faces of the ends 13 and 14 are tapered at 70 to be received by the flaring faces 170 of the ends 17 and 18, respectively, of the tube 69. At the inner end of each of the faces 170 of the ends 17 and 18, there is provided a seal or washer 71 composed of some suitable synthetic rubber, formed by polymerization of chloroprene such as is sold on the market under the name "Nyprene" or "Hycar." In the next place, in each of the ends 13 and 14 there is provided an annular collar 72 having a central opening 73, having a channelled guide 74 extending outward and a conical valve seat 75 formed on the inner end of the collar 72 to receive the valve head 76 mounted on the stem 77 extending through the channel of the guide 74 and provided with a collar or disk 78 fixed on the stem 77, between which collar 78 and the guide 74 there is disposed the coil spring 79 normally to maintain the valve head 76 on the seat 75. Each of the ends 17 and 18 has a collar 80 with a central opening 81 provided with a channelled guide 82 to receive the stem 83 having a valve head 84 on its inner end to engage the valve seat 85 formed on the inner face of the collar 80 and a disk 86 on its outer end between which disk 86 and the guide 82 there is disposed the coil spring 87 normally to maintain the head 84 on the valve seat 85. Since the outer end of the stem 77 extends beyond the disk 78, obviously when the two complementary ends 13 and 17, or 14 and 18, are brought together as shown in Fig. 3, the free end of the stem 77 will engage the disk 86 when either spring 79 or spring 83 will first compress and thereupon the other spring compress to displace the valve heads 76 and 84 from their respective valve seats, or else both coil springs 79 and 83 will compress simultaneously to displace the valve heads 76 and 84 into the positions shown in Fig. 3. With this arrangement, immediately that the casing 2 is removed, the complementary valves will close the ends 13, 17, and 14, 18, and in turn

when the casing 2 is replaced, the complementary valves will open each other to clear the passage from the tube 15 to the tube 69 and back to the tube 16, and in turn impinge the seals 71 between the annular edges 88 of the ends 13 and 14 and the shoulders 89 at the inner ends of the flaring faces 170 to effect leak-proof seals between the complementary set of ends 13 and 17 and the complementary set of ends 14 and 18.

Since one of the objects of the present invention is to preserve the sanitary advantage of the construction illustrated in applicant's prior issued patent aforesaid, in the consequent frequent separation of the casing section 2 from the casing section 1 in the interest of protecting the valve units having the valve heads 76 and 84 and the stems 77, the projection 9 and enlargement 11 protrude further from their associated contact faces 19 and 20 than the protruding portions 13 and 14 of the inlet and outlet conduits 15 and 16 as well as the protruding portions of the stems 77 protrude from their associated faces 19 and 20. Since the projection 9 protrudes further than the enlargement 11, it will be seen that in the process of replacing or reconnecting the casing section 2 to the casing section 1, the projection will first locate the casing section 2 when entering the recess 20 and the enlargement 11 will thereupon aline the casing section 2 relative to the casing section 1 so that the protruding portions 13 and 14 of the conduits 15 and 16 as well as the stems 77 will be truly alined with the openings 17 and 18 of the casing section 2 and thus positively protect the protruding portions 13 and 14 as well as the valve stems 77 from injury when reconnecting the casing section 2 to the casing section 1, and in addition thus also positively protect the valve units having the valve heads 76 and 84. The importance of this feature is of course, obvious when consideration is taken of the need for repeatedly effecting a fluid-tight connection between the protruding portions 13, 14 and the ends 17 and 18 of the conduit 69.

It is obvious that various changes and modifications may be made to the details of construction without departing from the general spirit of the invention as set forth in the appended claims.

I claim:

1. A coupling for a meat chopper comprising a stationary casing section and a removable casing section, said sections having contacting complementary faces, one of said sections being provided with a first recess in its face, a projection on the other section extending from its face and engaging in said first recess, one of said sections being provided with a second recess in its face spaced from said first recess, an enlargement of less length than said projection on the section opposite to said second recess and engaging in said second recess, each of said sections having at least one conduit therein opening through its face, said conduits registering with one another, and one of said conduits having a protruding portion extending from the face associated therewith, said protruding portion being of less length than either said projection or said enlargement whereby when said sections are assembled for engagement of said complementary faces with one another, said protruding portion will be alined for registration with the conduit of said other section and be protected from injurious contact with said other section while being so alined for registration with the conduit of said other section.

2. The coupling as set forth in claim 1 in which said enlargement and said protruding portion extend from said stationary section and said enlargement is disposed between said projection and said protruding portion.
3. A coupling for a meat chopper comprising a stationary casing section and a removable casing section, said sections having contacting complementary faces, one of said sections being provided with a first recess in its face, a projection on the other section extending from its face and engaging in said first recess, one of said sections being provided with a second recess in its face spaced from said first recess, an enlargement of less length than said projection on the section opposite to said second recess and engaging in said second recess, said stationary section having feed and return conduits therein opening through its face, said removable section having a wall forming a main chamber and a conduit in said wall having feed and return ends in its face registering with the feed and return conduits in the other face, and the conduits of said stationary section having protruding portions extending from its face, said protruding portions being of less length than either said projection or said enlargement whereby when said sections are assembled for engagement of said complementary faces with one another, said protruding portions will be alined for registration with the conduits of said other sections and be protected from injurious contact with said other section while being so alined for registration with the conduits of said other section.
4. The coupling as set forth in claim 3 in which a clamping device is associated with said projection for clamping said complementary faces into intimate engagement with one another after being assembled.
5. The coupling as set forth in claim 3 in which complementary check valves are disposed in said protruding portions and in said feed and return ends having valve stems protruding beyond the outer ends of said protruding portions, which stems and protruding portions together are of less length than either said projection or said enlargement whereby when said sections are assembled said stems similarly will be protected from injurious contact with said other section while being alined for registration with the check valves in said feed and return ends.
